WAVEGUIDE POWER DIVIDER

Robert D. Hatcher, Washington, D. C., assignor to the United States of America as represented by the Secretary of the Navy

Application May 23, 1952, Serial No. 289,702

2 Claims. (Cl. 333—7)

(Granted under Title 35, U. S. Code (1952), sec. 266)

The invention described herein may be manufactured and used by or for the Government of the United States of America for governmental purposes without the payment of any royalties thereon or therefor.

The present invention relates generally to electromagnetic energy transmitting waveguides, and more particularly to a variable power divider for coupling variable amounts of power between two sections of waveguides, or for diverting a desired amount of power being transmitted through one waveguide into another waveguide, and is related to application Serial No. 289,703, filed May 23, 1952.

In waveguide transmission of electromagnetic energy, it is frequently desired to couple energy from one section of waveguide into a second waveguide channel, or to decrease the power of energy transmitted along one waveguide by diverting or coupling a portion of the energy into a separate waveguide channel. In such applications, it is further frequently desirable to be able to vary the proportions of diverted or coupled energy, as for example to effect a variable attenuation control of that energy in the initial waveguide channel reaching the power diverting or coupling point.

The present invention, being directed toward accomplishing the foregoing ends, has therefore as one object to provide for dividing waveguide transmitted electromagnetic energy from one waveguide channel into another in varying proportions as desired.

Another object of the present invention is to effect a variable power coupling of electromagnetic energy between sections of waveguide.

Another object of the present invention is to provide a variable power coupling between sections of waveguide simple in construction, easy of operation, positive in operation, and having a minimum number of parts.

Other objects and many of the attendant advantages of this invention will be readily appreciated as the same becomes better understood by reference to the following detailed description when considered in connection with the accompanying drawings wherein:

Fig. 1 is a partially cutaway isometric view of an exemplary embodiment of the present invention;

Fig. 2 is a longitudinal horizontal sectional view of the device shown in Fig. 1; and

Fig. 3 is a vertical cross-sectional view taken along line 3—3 of Fig. 2.

Referring to the drawings, there is illustrated a portion of each of two waveguide channels 10 and 11 which have been brought into longitudinal juncture at 12, there united into an integral structure, and the dividing walls removed. A short fixed partition 13 may be provided at one end of the juncture 12 along its longitudinal center. There is further provided along this center line two grooves or slots 14 and 15, one at the top and the other at the bottom of the juncture, running from the end of the partition 13 to the opposite end of the juncture. The end of the juncture 12 opposite from the partition

13 is provided with a slit opening 16 (Fig. 2), extending from top to bottom of the juncture, for receiving a movable partition 17 comprising the wall portion 18 and handle 19. The wall portion 18 may be formed of two elongated strips of metal 20 and 21, preferably rolled to curve along their shorter dimension, and secured together with their concave sides outward. The dimensions of the wall 18 are chosen such that when inserted into the juncture 12 through slit 16, the wall can extend therein up to and abut the end of short fixed partition wall 13, the opposed longitudinal edges of the movable partition sliding in the grooves 14 and 15. The curvature in strips 20 and 21 is formed to provide sufficient spring action to make good electrical contact with the grooves and hence the juncture walls and the waveguides, and to effect a frictional holding of the movable partition in its adjusted position.

The structure described thus provides for bringing two waveguide sections into conjunction with a movable partition separating the two waveguides at their juncture. By slidably adjusting the longitudinal position of movable partition 17 in the guideways or slots 14 and 15, the size of the opening or aperture between the two sections of waveguides can be readily adjusted at will, and by enlarging or diminishing this aperture the power coupling or division between the two waveguide sections is accordingly altered. As will be readily apparent to those skilled in the art, the position of the partition in the juncture 12, and thus the window or aperture size, can be vernier controlled for accurate power division or coupling, and further, can be remotely controlled by motor, solenoid, or mechanical linkage as desired.

Obviously many modifications and variations of the present invention are possible in the light of the above teachings. It is therefore to be understood that within the scope of the appended claims the invention may be practiced otherwise than as specifically described.

What is claimed is:

1. A waveguide power controller comprising two waveguide sections brought into juncture along a portion of their length, an opening being formed to interconnect the two waveguide sections along their juncture, the top and bottom walls of the juncture thus formed each having a groove running substantially along said opening, said juncture further having a slit opening at one end running between the top and bottom grooves, and means for converting said two waveguide sections into a single, undivided energy directing chamber, or alternatively, into an adjustably coupled energy dividing circuit, said means comprising a partition wall of electrically conducting material including two concavely bowed resilient strips having tangential contact along their median areas, and having their top and bottom edges slidably positioned in said grooves through said slit, varying the position of said partition in said grooves thereby varying the opening interconnecting said waveguide sections along said juncture to vary the electromagnetic power coupling therebetween accordingly.

2. A waveguide junction comprising two open-ended rectangular waveguide sections contiguous along their narrow sides for a portion of their length and having a common wall portion, an opening in said wall portion for electromagnetically interconnecting said sections, parallel longitudinal grooves formed in the opposite walls of said sections along said opening, and a slidable partition formed of two elongated strips of resilient conducting material secured together with their opposite edges diverging and resiliently contacting the sides of said groove for varying the electromagnetic power coupling between said sections.
